Office, Kitchen and Bedroom Design for Canteen. Standard 3. Nov. 1952

Design No. 339

Smith and Gleason of Le Roy N. Y.
Letters Patent. No 339. Dated Dec. 3. 1850.

The Schedule referred to in these Letters Patent and making part of the same.

To all whom it may concern:

Be it known that we, Morris Smith & Benona S. Gleason, of Le Roy, in the County of Genesee, and State of New York, have invented a new design of Cook Stove which we call the California air tight and we do hereby declare that the following is a clear, full, and exact description of the same, reference being had to the annexed drawings making a part of this specification, in which fig. 1. is a perspective view, fig. 2 & 3. the side doors, fig. 4. the side of the body of the stove, fig. 5. the front plate, fig. 6. the side of the oven, fig. 7. the oven door, & fig. 8. the front door. There are two doors exactly alike, but only one represented in fig. 8. There are also two oven doors exactly alike, but only one represented in fig. 7.

Having thus described the nature of our new design,

What we claim therein as new, and desire to secure by Letters Patent, is the design of ornament & configuration, constituting in construction a new design of Stove, substantially the same as herein described & represented in the annexed drawings.
